UNITED STATES PATENT OFFICE

EDWARD H. BINNS, OF PITTSBURGH, PENNSYLVANIA

PAVING TILE

Application filed September 18, 1930. Serial No. 482,791.

The present invention relates to improvements in composite tiles for paving purposes in which a shaped shell or container of metal, glass or other suitable material has molded 5 into it a concrete or other plastic material that will harden and intimately adhere to the shell or container to form a solid block.

The present invention comprises improvements in the detail construction of such composite paving tiles, the main feature of which improvements consists in a composite paving block having the hollow shell or container only partially filled with the hardened concrete or other plastic material to allow a 15 relatively small lower portion of the side walls to project beyond the body of the filling material to constitute an anchoring rim that will embed itself in the ballast when the paving tile is laid and thereby effectively 20 prevent its lateral displacement.

Another feature of the present invention consists in so forming the hollow shell or container of metal or other suitable material (preferably of metal) by molding or otherwise to afford relatively thick walls for the top or wear-sustaining portion and the immediately adjacent parts of the side walls which connect with and support the top wall, said side walls being slightly tapered from 25 their thick top adjoining portions to their lower relatively thin edges which form the ballast engaging displacement resisting rim. To further strengthen the hollow shell or container it is formed with internal strength- 30ening webs which are preferably cast integral with both the top and side walls, said webs or ribs being widest in their parts that span the internal angle between the top and side walls and tapered toward their ends into the 35 surfaces of said walls. I have found it desir- 40able to have some of the strengthening webs extend approximately the entire height of the side walls, while others afford sufficient rigidity to the box-like shell or container by 45 their termination short of the entire height of said walls.

Another feature of the present invention comprises the formation in the top wear- 50resisting surface of the improved paving tile of a relatively small key-way extending

through the top wall and communicating with a key-chamber formed by a box-like projection on the inner surface of the top wall, said key-way and key-chamber being entirely closed off from the hollow interior of the shell or container into which the cement or other plastic material is molded. The key-way preferably of narrow elongated shape is designed to receive a complementary key which can be passed through the key-way and turned in the key-chamber so that the wings or projections of the key will engage the under surface of the top wall in the key-chamber and by the application of a suitable tool raise and lower the composite tile. This 55 key-way and key-chamber are placed approximately above the center of gravity of the composite tile, that is, approximately at a point within the intersecting vertical, transverse and longitudinal planes extending 60 through the center of gravity of the tile.

In practically utilizing the improved composite tile in paving a rolling mill floor it has been found desirable to make the tiles large and heavy to reduce to a minimum the 65 required number of tiles and joints to pave a given surface and to better withstand the heavy wear that the pavement is subjected to. In practice I have made and used composite tiles embodying my invention that are 70 approximately 17 inches square by 5 inches deep which when partially filled with hardened concrete have weighed approximately 150 pounds. The use of the key in the key-way and chamber as above described facilitates 75 handling these heavy composite tiles both in originally laying the pavement and subsequently in removing individual tiles for repair or other reasons.

In order that the invention may be fully understood it will first be described with reference to the accompanying drawings and the novelty afterwards pointed out more particularly in the annexed claims.

In said drawings

Figure 1 is a detail plan view illustrating one form of pavement made with the improved composite tiles;

Figures 2 and 3 are similar detail views

showing modified plans of pavement made with the improved composite tiles;

Figure 4 is an inverted plan view of a hollow shell or container forming part of the improved composite tile ready to receive the partial filling of concrete;

Figure 5 is a vertical transverse sectional view of the tile of Figure 4 showing the partial filling of concrete molded in place and the tile in normal service position with its open bottom presented downwardly;

Figure 6 is a detail view partially in section showing the lifting key turned at right angles to its position shown in Figure 5;

Figure 7 is a detail sectional view taken on the line 7-7 of Figure 6;

Figure 8 is a view similar to Figure 4 showing a shell or container of triangular shape;

Figure 9 is a view similar to Figure 4 showing a shell or container of oblong shape.

In making the improved composite tile I first mold or otherwise shape a shell or container of the desired size and design. I prefer to form the hollow shell or container of cast iron which, as shown in Figures 4, 5 and 6 of the drawings, is in the form of a hollow square open-bottomed box of which 1 is the wear-resisting top plate formed integral with the four downwardly projecting side walls 2, which latter are preferably tapered in thickness from the top plate 1 to the bottom open rim 3. The top plate 1 and side walls 2 are rigidly braced by means of the internal strengthening webs or ribs 4 which are cast integral with said top and side walls and are shaped to taper toward their ends to merge into the walls with which they are attached. The central strengthening webs or ribs 4 on each side wall are lengthened slightly to extend to the extreme lower thin edge or rim 3 of the side walls.

The top wear-resisting surface 1 of the shell or container has cast upon its inner surface a small box-like key-chamber 5, the walls of which are integral with the top plate 1 and are braced by the webs or ribs 6 radiating from the circular key chamber and cast integral with the under face of top plate 1 to further strengthen said top plate. Communicating with the key chamber 5 is an oblong key opening 7 extending through the top wall 1 and in communication with the key-chamber 5. This key opening 7 is made relatively small and narrow so as not to interfere with the load supporting surface of top plate 1.

In Figure 8 is shown a triangular shell or container 10 having the same described characteristics as the square form shown in Figures 4, 5 and 6. In Figure 9 is shown an oblong form of shell or container 11 which also has the same characteristics above described with reference to the square form. These several simple shapes of tiles are selected as desirable for the convenient laying of

pavements of simple design as shown, for example, in Figures 1, 2 and 3 of the drawings hereinafter referred to.

The hollow shell of the desired shape has molded into it a sufficient quantity of concrete or other suitable hardening plastic such as indicated at 15, the same being carefully molded to completely embed the wall of key-chamber 5 and the strengthening webs or ribs 4 and 6. The molded material 15 only partially fills the interior cavity of the shell or container, leaving the lower thin portions of side walls of the container to project in the form of anchoring rims which when the composite tile is laid will embed itself into the ballast and thereby prevent lateral displacement of the tile. In filling the shell or container with cement I have found it desirable to start with a surplus of water in the inverted shell or container, this excess of water causing a more intimate adhesion of the hardened concrete with inner surface of the cast iron shell or container.

In Figures 5, 6 and 7 is a tile lifting key comprising a bar formed at its lower end with oppositely projecting wings 9 of the proper size and shape to be inserted in the key opening 7 of the composite tile. Upon inserting the key in opening 7 it is turned 90° upon its axis in key-chamber 5 to move the wings 9 out of alignment with the key opening into engagement with the overhanging wall 1 as shown in Figure 7. With the key thus engaged in the key-chamber the tile can readily be lifted by any simple mechanical means placed in engagement with the key.

In Figure 1 is shown a pavement with the improved tile set in inclined rows and with the tiles of adjacent rows breaking joints. In the plan of pavement shown in Figure 1 the triangular tiles 10 are conveniently used along the walls or outer borders of the pavement, while the oblong or half-size tiles 11 are used at intervals in starting the break joint arrangement of the rows of the main tiles 1.

In Figure 2 a plan of pavement is shown in which the square tiles 1 are laid in rows parallel to the walls or other enclosing borders and in which the tiles break joint in adjacent rows. To effect the break joint arrangement in this plan of pavement every other row is started with a half tile 11 of oblong shape.

In Figure 3 a plan of pavement made with the improved composite tiles is shown in which the tiles are laid in diagonal rows with continuous lines of joints in which case the triangular tiles 10 are used on the outside borders of the pavement.

The chief advantages of the improved composite tiles are great strength and economy of manufacture and use. With the tile lifting key the tile can be readily moved into and

out of position either when originally laying the pavement or in moving individual tiles for repairs or otherwise, such as the necessity of lifting a row of tiles for the purpose of 5 laying a pipe line. The projecting anchoring rim of the side walls of the tiles effectively engage the ballast or prepared surface on which the pavement is laid and prevent lateral displacement. The improved tile being of great weight and substantial depth, it 10 will effectively hold itself in proper position in the pavement without additional means of securing it. It is proposed to use improved composite paving tiles in places 15 where formerly a well-known cast iron floor plate has been used for paving. These cast iron floor plates are subject to warping either as the result of the foundry operation or from being peaned after being laid as a pavement, 20 the constant blows of the wheels of traffic producing this warping result. The improved composite tiles are not subject to this warping defect because of the particular construction described.

25 I claim:—

1. A composite tile for paving comprising a shaped shell or hollow container having top and side walls and open at the bottom, said top wall having a key opening approximately 30 in the intersecting vertical longitudinal and transverse planes through the center of gravity of the tile, a key receiving chamber formed on and projecting inwardly from the top wall and communicating with said key opening, said key-receiving chamber being closed from the shell interior and a suitable filling material molded in said shell or container around the wall of said closed key chamber and partially filling the same, in 35 combination with a tile lifting key fitting said key opening and adapted to be turned in said chamber into engagement with said top wall.

2. A composite tile for paving comprising a shaped shell or hollow container having top 40 and side walls and open at the bottom, said top wall having a key opening approximately in the intersection of the longitudinal and transverse vertical planes through the center of gravity of the tile, an undercut key receiving chamber in communication with said key opening, said chamber being formed by an integral trussed wall formed on the inner face of said top wall and closed from the shell interior, and a filling material molded into 45 said shell or container.

EDWARD H. BINNS.
